US00D556322S

(12) **United States Design Patent** (10) **Patent No.:** **US D556,322 S**
(45) **Date of Patent:** **** Nov. 27, 2007**

(54) **TIP OF A PHACOEMULSIFICATION NEEDLE**

(75) Inventor: **Takayuki Akahoshi**, Tokyo (JP)

(73) Assignees: **Ravi Nallakrishnan**, Westmont, IL (US); **Takayuki Akahoshi**, Tokyo (JP)

(**) Term: **14 Years**

(21) Appl. No.: **29/220,376**

(22) Filed: **Dec. 30, 2004**

(30) **Foreign Application Priority Data**

Oct. 4, 2004 (CH) 131259

(51) **LOC (8) Cl.** **24-02**

(52) **U.S. Cl.** **D24/144; D24/112**

(58) **Field of Classification Search** D24/144, D24/112; 600/459, 471; 604/82, 118, 119, 604/272, 542, 264, 257, 35, 258, 902, 22, 604/167; 606/169, 107, 161, 28, 29, 39, 606/45, 27, 81

(57) **CLAIM**

The ornamental design for a tip of the phacoemulsification needle, as shown and described.

DESCRIPTION

FIG. 1 is a perspective view of a tip of a phacoemulsification needle showing my new design;

FIG. 2 is a left view thereof;

FIG. 3 is a top view thereof;

FIG. 4 is a right view thereof;

FIG. 5 is a bottom view thereof;

FIG. 6 is a front view thereof; and,

FIG. 7 is a rear view thereof.

The broken line showing is for illustrative purposes only and forms no part of the claimed design.
